UNITED STATES PATENT OFFICE

HARRY T. PARKER, OF OAKLAND, CALIFORNIA, ASSIGNOR TO THE STANLEY WORKS

MORTISING MACHINE

Application filed November 19, 1928. Serial No. 320,513.

My invention relates to a device for cutting mortises, such as are used in window frames for the reception of sash pulleys or the like.

5 An object of the invention is to provide a mortising machine which cuts a slot and machines a countersunk surface on a window sash in a single operation, said countersunk surface to receive the faceplate of the sash 10 pulley and to extend beyond the ends of the slot, thereby to provide a large, undiminished bearing surface for the faceplate of the sash pulley and a firm support for the screws in said faceplate.

15 Another object of the invention is to provide a device of this character which will simultaneously cut a plurality of mortises in a single operation.

20 A still further object of the invention is to provide a device of this character that is of compact and inexpensive construction and positive in operation.

25 With the above mentioned objects and other objects in view, the invention consists in the novel construction and combination of parts, hereinafter described, illustrated in the accompanying drawings, and set forth in the claims hereto appended, it being understood that various changes in the form, 30 portion, size, and minor details of construction within the scope of the claims, may be resorted to without departing from the spirit, or without sacrificing any of the advantages of, the invention.

35 In the drawings:

Figure 1 is a front elevation of the device of my invention;

Figure 2 is a sectional view of my device taken on the line 2-2 of Figure 1;

40 Figure 3 is a view of my device partially broken away, taken on the line 3-3 in Figure 2, and showing the means for operating the material-holding device of my invention;

45 Figure 4 is an enlarged sectional view taken on the line 4-4 in Figure 1, showing the construction of the mortise-cutting device; and

50 Figure 5 is a perspective view of a piece of material showing a countersunk mortise cut by my device.

In carrying out my invention, I provide a frame member 1 having spaced upright supporting members 2 and 3 extending therefrom. Parallel rods 4 and 5 extend transversely between the supporting members 2 and 3, and are secured to said supporting members.

55 Slidably mounted on the rods 4 and 5 is a tool support having mortise-cutting member or carriage 6, said member comprising oppositely disposed supporting members 7 and 8. Said supporting members are adapted to be slidably positioned on the rods 4 and 5, as shown in Figures 1 and 2. The supporting members 7 and 8 are provided with downwardly extending lugs 9 and 10 having bores therein to receive the rods 4 and 5. The supporting member 7 and 8 are held in a suitably spaced relation by parallelly disposed cross members 9' and 10'. The cross members 9' and 10' are removably secured to the inside faces of the supporting members 7 and 8, in spaced relation to each other. Said cross members are secured to the supporting members in any suitable manner such as by bolts 75 11. Cutter bearing members 12 are removably secured to the cross members 9' and 10' by bolts 13, said cutter bearing members being positioned in alignment with each other and held spaced by the cross members 9' and 10'. It will be noted that the cross member 9' is adapted to be vertically adjusted with respect to the corresponding cross member 10' by means of slots 14 disposed in the supporting members 7 and 8.

85 A connecting rod 15 is pivotally secured by a bolt 16 to a cross member 17 extending transversely between the lugs 9 of the supporting members 7 and 8. The bolt 16 is centrally located between said supporting members and passing through a slot in the rod 15. The connecting rod 15 is also pivoted at 18 to a bracket 19 fixed to the frame 1. Said second pivot is positioned below the pivot 16 and in vertical alignment therewith. The other end of said connecting rod is adapted to fit in a T-shaped bearing member 20 eccentrically secured to a belt pulley 21. Said bearing member is rotatable and is adjustably secured in a slot 22 in said belt 100

pulley by means of a bolt 23. It will now be seen that rotation of the belt pulley 21 will cause the connecting rod 15 to oscillate around the pivot 19 thereby causing a reciprocating motion of the mortise-cutting member 6.

A cutting tool shaft 24 is rotatably supported in the bearing 12, and a pulley 25 is attached to the end of the shaft 24 adjacent to the side of the frame on which the pulley 21 is supported. Pulley 21 transmits the power to pulley 25 by any conventional means such as a belt. A cutting or slotting tool 26 is screwed into the shaft 24 at the opposite end thereof. The cutting tool 26 comprises two parallel blades 27 extending from a shank 28. Said blades are sharpened on the outside edges and around the point thereof for the purpose to be hereinafter described. A gear 29 is fixedly secured to the central portion of the shaft 24 and meshes with gears 30, said gears 30 to be in turn fixedly secured to the shafts 31 disposed on the opposite sides of the shaft 24 and rotatably supported in the bearing 12. The counterboring tools 32 are screwed into the ends of the shafts 31 adjacent to and on the opposite sides of the cutting tool 26. Each of the counterboring tools 32 comprises two parallel blades 33, said blades to be much shorter than the blades 27, as is clearly shown in Figure 4, and a shank 34 to support the blades 33 and to be screwed in the shaft 31. It is evident that when the pulley 25 is rotated, the rotation is simultaneously transmitted to all three cutting tools.

A platform 35 is attached to the rods 36, said rods being slidably supported in said upright supporting members 2 and 3. The ends of the rods 36 are tied together by means of a cross bar 37. A hand wheel screw member 38 is fixedly secured to the cross tie 37 and extends therethrough, said screw member to be threaded in a bracket 39 fixedly supported on the frame 1. Springs 40 are disposed around the rods 36 outside of the uprights 2 and 3 bearing against said uprights and against a collar 41 attached to the ends of the rods 36. These springs tend to urge the rods 36 and the carriage 35 towards the left, referring to Fig. 1. The platform 35 comprises a carriage 42 having an upright carriage member 43 at one side thereof and spaced from the edge of said carriage 43, so as to form a rectangular support for the pulley style 44. As shown in dotted lines in Figure 2, the pulley style to be drilled is supported on the carriage 42. Clamps 45 are disposed at the opposite ends of the carriage 42 and spaced therefrom so as to allow the pulley style 44 to be slipped between the upright member 43 and the clamps 45. The pulley style is then gripped by the pressure of the clamps 45 to be applied by means of shafts 46, operated by the eccentric handle 47. The eccentric handle 47 is pivotally se-

cured to a cross shaft 48, said cross shaft 48 to be attached to the ends of the shafts 46. The eccentric portion of handle 47 bears against the metal plate 49. The turning of the handle presses the eccentric against the carriage and reciprocates the clamping shafts 46 therein so as to actuate the clamps 45.

The invention operates as follows: The pulley style 44 is secured to the work support or carriage 35 as heretofore described. The carriage 35 is advanced towards the mortising tool 6 by the turning of the handwheel 38. The cutting tools are rotated by the pulley 21 and pulley 25 and are reciprocated by means of the connecting rod 15. The pulley style 44 is slowly pressed first against the slotting tool 26, said tool cutting a slot 49 thru the pulley style 44 as shown in Figure 5. Near to the end of the slotting operation by the tool 26, the countersinking tools 33 reach the pulley style 44. When the carriage 35 is further advanced, the slotting tool 26 cuts thru the style while the counterboring tool 33 cuts a countersunk surface 50 as shown in Figure 5. The countersunk surface extends sufficiently far beyond the ends of the slot to provide a large bearing surface for the pulley faceplate and the fastening screws therein. It is evident that by changing the spacing of the cutting tools, the radius of the countersunk shoulder 50 may be increased so as to provide more clearance outside of the ends of the slot 49.

The above mortising is accomplished by a single operation, and in a single machine readily operated by one operator who first clamps the pulley style 44 on the carriage 35. Then by simply turning the handwheel 38, both the slotting and countersinking of the pulley style is completed. The cutting tools are so designed as to allow the machining of a large countersunk shoulder simultaneously with the cutting of the slot thru the pulley style.

Having thus described my invention, what I now claim and desire to secure by Letters Patent is:

1. In a mortising machine, a tool support, a work support, a rotatable slotting tool carried by said tool support for forming an elongated slot, a rotatable counterboring tool to each side of said slotting tool for forming a countersink which extends considerable distances beyond the ends of the slot, the axes of said tools being parallel and positioned in a single plane, said cutting tool and counterboring tools having side and end cutting edges and said slotting tool being of lesser diameter than and projecting beyond said counterboring tools, means for reciprocating one of said supports in the direction in which said tools are spaced apart whereby said tools will cut laterally as they are fed into the work, and means for feeding one sup-

port towards the other, said slot and marginal countersink being formed in the single operation of relatively feeding the tools into the work.

2. In a mortising machine, a reciprocating tool support, a slotting tool journaled therein for forming an elongated slot, a rotary counterboring tool to each side of said slotting tool for forming a countersink extending considerable distances beyond the ends of the slot, all of said tools being routing tools having side cutting edges, said slotting tool extending beyond said counterboring tools, said tools having their axes lying in the plane in which the tools are reciprocated and being at right angles to the line of reciprocation, said tools being arranged for cutting the slot and countersink in the single operation of feeding the tools into the work without interruption.

In testimony whereof I affix my signature.

HARRY T. PARKER.
